EXTENSIBLE BUCKLE

Ernest Nukanen, New York, N. Y.

Application September 11, 1946, Serial No. 696,277

2 Claims. (Cl. 24—163)

1

This invention is a safety expansion spring device. My invention relates to expansion devices and more particularly to a safety expansion spring device that has many uses and applications.

One objective of my invention was to design an expansion device that could be manufactured in a variety of sizes so that it could be adapted to many uses. A unique feature of my device is that it can be adapted for use as a shoe buckle, belt buckle or in connection with any type of machine that demands an enclosed spring member.

It has many advantages over the conventional belt buckles that have spring assemblies in that the spring mechanism is entirely concealed in the buckle. This is a distinct advantage over those spring assemblies that are merely covered by a flap of the belt or not concealed at all. Some of the conventional type now in use do not protect the wearer's clothes from the constant friction of the spring assembly against the clothing of the wearer. Due to the fact that my device is entirely enclosed, its outside construction is smooth, offering no sharp edges or projections which would cause excessive wear or hardship on the wearer's apparel.

My device is strongly constructed and the type of unique spring used has many apparent advantages over the coil springs which are ordinarily used with this conventional type of buckle.

In the event my invention is used in connection with machinery, it has the added feature of safety in that the spring mechanism is entirely enclosed, and should the spring break, it would be impossible for anyone to be injured due to flying parts. A further advantage of my device is that it is readily assembled and will be inexpensive to manufacture.

Other apparent advantages and unique features of my invention will be disclosed as I proceed with the description.

Referring to the drawings—

Figure 1 shows a face view of my device in section.

Figure 2 shows a section view on line 2—2 of Figure 1.

Figure 3 shows a section view on line 3—3 of Figure 2.

Figure 4 shows a modification of the spring assembly as indicated on line 3—3 of Figure 2.

Figure 5 shows a horizontal section view through Figure 4 showing the complete assembly.

Figure 6 shows a modification of the spring assembly as indicated on line 3—3 of Figure 2.

2

In Figure 1 I have shown a face view of my device utilized as a belt buckle 10. The housing 11 of the belt buckle 10 is shown in its preferred form as approximately rectangular in shape. However, any desired shape or configuration that is required may be utilized. The housing 11 ordinarily would be constructed from metal. However, plastics or other similar materials that would fulfill the purpose could be used.

10 The housing 11 is a hollow structure completely closed except for the slot 22 on its upper wall and openings 23 located at the extreme ends of the side faces. The slot 22 guides the pin 14 which is attached to the sliding plate 12 of the spring assembly. The plate 12 is free to move lengthwise in the housing 11, with its movement being controlled by pin 14 which is affixed to the plate and extends through the top of the housing 11. The longitudinal movement of the pin 14 is guided by slot 22 in the housing 11.

15 As shown in Figure 3, the width of the plate 12 is slightly less than the width of the inside of the housing 11 so that the plate is free to move lengthwise within the housing 11.

20 In its preferred form the plate 12 is roughly square in shape and its length is approximately half the length of the housing 11. The pin 14 is affixed in the center near one end of the plate. Extending from the corners of the opposite end 25 diagonally toward the pin 14 are two angular cutouts 13. These cutouts 13 form the guides that control the movement of the spring 16. The spring member 16 consists of a section of spring steel or other similar material formed approximately in the shape of a triangle with one angle being cut off and the open ends 26 being curved outwardly. The base of the spring 24 is held firmly in place through two pins 15 that prevent the base of the spring from longitudinal movement when the sliding plate 12 is moved. The legs 25 of the spring are positioned in the cutouts 13 and as the plate 12 is moved away from the base 24 of the spring 16, the legs 25 of the spring are forced out, with the curved ends 26 30 of the spring 16 riding along the outer sides of the cutouts 13.

35 As soon as the tension has been removed, the spring 16 will pull the plate 12 back to its normal position.

40 As shown in Figure 2, the upper portion of the pin 14 is affixed to an upper plate 17. In the center of plate 17 is mounted a gripping member 19 with two upturned curved ends 27 over which the belt 20 is guided. The upturned ends 45 27 serve to grip the belt and prevent any lateral

movement of the belt while being held by the buckle. At the opposite ends of the upper plate 17 are bars 18 and 18' bridging from one side of the plate 17 to the other side and leaving a space between the plate 17 and the bar 18 and between the plate 17 and the bar 18' for the belt 20. Normally the belt 20 would be directed in under bar 18 over the gripping member 19 and out under the opposite bar 18'. Once the belt 20 has been firmly fastened in place around the wearer's waist, any expansion will cause the upper plate 17 which is connected through the pin 14 to the sliding lower plate 12 to move in a direction against the pull of the spring 16, while the housing 11 will move in the opposite direction.

As shown in Figure 2, one end of the belt 20 is fastened to the left attachment 21 whose ends 28 are anchored in the housing 11 through openings 23.

In Figure 4 I have shown a modification of my device consisting of a housing 41 and a slidable lower plate 40. The lower plate 40 is slightly less in width than the housing and approximately the same length as the housing. One end of the plate 40 has a belt attachment 45 which is connected by two legs 46 to the opposite end of the plate which contacts the spring member 42. The spring member 42 is the same type as previously described and is held in position by pin 44 held in apertures in the upper and lower walls of the housing. The legs of the spring member 42 are positioned in the diagonal cutouts 43 of the plate 40.

Figure 5 shows a sectional view of Figure 4 showing the upper plate 47. Mounted on either side of the housing 41 are supports 48. Through the supports 48 is a rod 49 on which the upper plate 47 is pivoted. The belt is brought to the buckle through one end under the bar 50 and over the gripping member 51 and out under bar 50'.

Figure 6 shows another modification of my device utilizing a different shaped spring. This modification is used in conjunction with the same type of housing as shown in Figure 1 and the pin 54 is similar to pin 14 in that the lower portion is attached to the sliding plate 53 and the upper portion to the upper plate. The unique feature of this modification is the structure of the spring 52 which, due to its unique shape, enables a spring

of great strength to operate in a restricted area.

It will be appreciated that I have outlined the preferred form of my device and that minor changes may be made without departing from the principal scope of my invention.

I claim:

1. A belt buckle or the like comprising a spring member, a housing having equidistant upper and lower walls, slidable upper and lower plates, the upper plate adapted to slide on the outer face of the upper wall and the lower plate adapted to slide in the space between said upper and lower housing walls, said lower plate being apertured to form angular cutouts, said cutouts converging toward each other at their inner ends, said spring member being substantially U-shaped and being fastened at its base to one end of the housing, the legs of said spring being positioned in said cutouts, pin means connecting said upper and lower plates, the movement of said pin means being controlled by a slot cut in the upper housing wall, and said upper plate being equipped with means for securing the belt.
2. A belt buckle or the like comprising a spring member, a housing having equidistant upper and lower walls, an upper plate and a lower plate, the lower plate adapted to slide in the space between said upper and lower housing walls, said lower plate being formed with cutout portions converging toward their inner ends, said housing being equipped with means to secure a belt, said spring member being substantially U-shaped, the base of said spring being anchored to one end of said housing, the legs of said spring member being positioned in said cutouts, pin means connecting said upper plate to said lower plate through a slot in the upper wall of said housing, and gripping means on said upper plate for securing a belt.
